George C. Heimke

UNITED STATES PATENT OFFICE.

PHILIP ZELEZNOFF, OF PHILADELPHIA, PENNSYLVANIA.

LIFE-SAVING DEVICE.

1,372,469.

Specification of Letters Patent. Patented Mar. 22, 1921.

Application filed October 7, 1920. Serial No. 415,277.

To all whom it may concern:

Be it known that I, PHILIP ZELEZNOFF, a citizen of Russia, residing at Philadelphia, county of Philadelphia, and State of Pennsylvania, have invented certain new and useful Improvements in Life-Saving Devices, of which the following is a specification.

The present invention relates to improvements in life saving devices, particularly inflatable garments, and it is the principal object of the invention to provide a device of this character which is of a simple and inexpensive make, and which can be quickly and easily converted from a bathing suit 15 into a life saving garment, when occasion arises.

Another object of the invention is the provision of a device of this character which is equipped with means for preventing an 20 inconvenient and importunate sagging of the garment when it is to be used as a life saving device.

For further comprehension of the invention, and of the objects and advantages 25 thereof, reference will be had to the following description and accompanying drawing, and to the appended claim in which the various novel features of the invention are more particularly set forth.

30 In the drawing, forming a material part of this disclosure—

Figure 1 is a front view of a garment constructed according to the present invention.

35 Fig. 2 is a rear view thereof, and

Fig. 3 is a section along line 3—3 of Fig. 2.

As here shown, my improved life saving garment comprises a one piece suit 10 provided with short sleeves 11 and leg parts 12 provided with elastic bands 13 to close the lower ends of the leg parts around the wearer's limbs. The front of the garment is provided with the customary reinforcement band 14 allowing a closing of the garment in front by means of the buttons 15 or the like.

To the inner rear wall of the garment an inflatable rubber bag 16 is secured provided 50 with a channel 17 intermediate its ends for the passage of a belt 18, or the like, which is adapted to be closed at the front by the customary buckle and strap connection 19 adapted to hold the inflated rubber bag in adjusted position on the body of the wearer, so 55 that it may not sag and impede the swim-

ming or other motions of the person's arms and legs. From the upper edge of the rubber bag an elastic tube 20 is guided over the shoulder of the wearer to the front, where 60 it is held in place by means of an eye 21 or the like, fastening means, and ends in a mouth piece 22 for inflation of the bag, and reinforcing rings or washer pieces 23 and 24 are secured to the garment at the rear and 65 front thereof, at the places where the tube 20 leaves the garment, and where the eye 21 is secured to the same respectively. The mouth piece is rotatable and constitutes a valve which when turned in one direction 70 opens the passage into the tube 20 and in the other direction closes the same to prevent the escape of air.

It will be apparent that changes may be made in the general arrangement of the 75 parts of which my improved garment is made or in the construction of the minor details without departing from the scope and spirit of my invention.

Having thus described my invention, what 80 I claim as new and desire to secure by Letters Patent of the United States is as follows—

A device of the character described comprising in combination with a one-piece 85 bathing suit, an inflatable rubber bag secured to the inner rear wall of the garment over the back of the wearer, said bag having a closed channel intermediate its ends, a belt passed through said channel and 90 adapted to be closed at the front part of the garment to prevent sagging of the inflated bag, a flexible tube secured to the rear of said bag near the upper edge thereof, a washer at the place of securing said tube to 95 said bag, said tube guided over the shoulders of the wearer, a guide eye at the front of said garment for said tube, a strengthening washer at the place where said guide is secured to the garment, a mouth piece providing a valve for closing said mouth piece against the escape of the air from said bag, means for buttoning the garment over the front part of the body of the wearer, and elastic bands for closing the leg parts of the 100 garment over the limbs of a person.

In testimony whereof I have affixed my signature.

PHILIP ZELEZNOFF.

Witness:

M. H. ROHEN.
